UNITED STATES PATENT OFFICE

102,729

DESIGN FOR A REAR VIEW MIRROR FRAME

Henry M. Pemberton, Fayetteville, N. C., assignor
of one-half to Phil Gibbons, Hamlet, N. C.

Application June 9, 1936, Serial No. 63,178

Term of patent 14 years

To all whom it may concern:

Be it known that I, Henry M. Pemberton, a citizen of the United States of America, residing at Fayetteville, in the county of Cumberland and State of North Carolina, have invented a new, original, and ornamental Design for a Rear View Mirror Frame, of which the following is a specification, reference being had to the accompanying drawing, forming part thereof, wherein:

The figure is a perspective view of a rear view mirror frame, showing my new design.

The right hand edge and the bottom portion of applicant's design are identical with the illustration of the design disclosed on the top portion and left hand edge of the design illustrated in the accompanying drawing of this application.

I claim:—

The ornamental design for a rear view mirror frame, as shown and described.

H. M. PEMBERTON.
